LEE J. BLACK, OF BEAUMONT, TEXAS.

FLUID-CIRCULATION UNIT FOR PUMPS.

Application filed December 2, 1924. Serial No. 753,469.

This invention relates broadly to an improved pump of the type utilized for handling slush in drilling wells, but has more particular reference to an improved fluid end or fluid circulation unit for such a pump.

Pumps of the above mentioned character are of the duplex design, the same embodying horizontal parallel cylinders and pistons 10 reciprocable therein, a plurality of separate fluid passages, wherein there is a separate fluid passage at each end of the cylinders, and these passages being scavenged by the pistons, which are usually of the double 15 acting type.

In devising the present improvement, it is my foremost aim to generally improve upon devices of this class, but to more particularly improve upon my prior Patent Number 20 1,202,153 granted to me on October 24, 1916.

So that the distinctions and structural advantages over that patent may be readily observed and appreciated, I believe it well to briefly review the structure there shown. 25 To this end, it will be seen that the fluid circulating unit there shown comprises a body said to be made up of pump cylinders, and a single casting bolted thereto and carrying all of the controlling valves. As is 30 characteristic of these units of fluid ends, the same embodies a single intake at the bottom and a single discharge at the top. The dual fluid passages for each cylinder are peculiarly designed in such a manner as to 35 alternately conduct and raise the fluid columns up between the opposed cylinders into a fluid trapping chamber. From here, the fluid descends under the action of suction thru restricted fluidways to one end of a 40 cylinder, and on the return or pressure stroke of the piston is forced up thru the very same fluidway into the top discharge chamber. Thus, a very long and tortuous course is taken, resulting in an inefficient 45 operation. This then is the main objection to the patented arrangement, and I therefore have developed and made a novel and more superior fluid end structure which is a 50 decided improvement and makes for greater efficiency in pump operation.

Broadly, I do this by providing a single casting for the piston cylinders, valves and mountings, and all fluid passages; and, as will be seen later, the passages are such as

to compel the fluid to follow the shortest 55 possible route in a direct line of travel from the point of entrance to the point of exit. In this way, the movement of the fluid is incessant and friction is reduced to a minimum.

The features of construction and the specific advantages derived from their use will be more prominently set out in the following description and rendered clear by the accompanying drawings.

In the accompanying drawings forming a part of this specification and in which like numerals are employed to designate like parts throughout the same:

Figure 1 is a perspective view of a complete slush pump showing my improved fluid end attached thereto.

Figure 2 is an end elevation looking in a direction toward the fluid intake and discharge end.

Figure 3 is a top plan view with certain of the cover plates removed.

Figure 4 is a fragmentary end elevation of the casting deprived of extraneous details.

Figure 5 is a side elevation of the complete 80 casting also eliminating certain details.

Figure 6 is a longitudinal vertical section taken approximately on the plane of the line 6-6 of Fig. 2.

Figure 7 is a view like Fig. 4, the same being in section to show the contour of the passages, chambers, etc.

Briefly described, the improved fluid end is restricted more particularly to a novel metal casting which comprises a pair of spaced 90 parallel barrels connected together at their open ends by a pair of substantially duplicate fluid conducting chests of special design. These chests are constructed to form ducts thru which fluid columns simultaneously 95 pass in opposite directions, and are of arcuate formation to conduct the fluid up and around the outer sides of the barrels. Connected to the central portions of the chests at the bottoms of the latter, is an intake 100 manifold, and connected to the central top portions is a discharge conduit. The specific construction of these and other details will now be described in detail.

Referring first to Fig. 1, it will be seen 105 that I have illustrated a complete slush pump embodying my improved fluid end. The pump, which is a conventional steam

pump, is designated by the character P, the valve box by the letter C, the valve operating mechanism by M, and the supporting rails by the letters R. These parts form 5 no part of the present invention.

The invention comprises a single metal casting which is designated generally by the numeral 1. It is made up of a pair of horizontal open ended barrels 2. These are 10 disposed in spaced parallelism and are of the same length. Connecting these barrels together at their opposite ends are substantially similar fluid chests 3 and 4 respectively. The outer chest 4 is slightly deeper 15 than the inner one 3. Otherwise, they are practically identical in configuration. An inwardly and upwardly inclined fluid intake manifold 5 is connected at its ends to the bottoms of the chests at the centers of the 20 latter. It is to be observed that this manifold is disposed on a plane below the barrels and is located between said barrels. Directly above the manifold in vertically spaced superposed relation is the discharge 25 conduit 6. The conduit is likewise arranged between the barrels and it and the manifold are of the same lengths as the barrels. With this arrangement, a very compact structure is had.

30 In end elevation, each chest appears to be transversely bowed, the bowed portions forming what may be called oppositely extending branches 7 and 8. These branches extend outwardly beyond the barrels. As 35 before intimated, these chests are formulated into passages, chambers, etc. Inasmuch as the fluidway from the intake to the discharge is identical in each instance, I prefer that the following description be in the 40 singular. In Figs. 4 and 7, I show one corner of the casting and it would be well to confine attention now to these views. In the branch 8, a comparatively short suction passage 9 is formed, the top wall thereof 45 being defined by a substantially flat and arcuate partition 10. The upper end of this partition terminates in a horizontal portion formed with a circular opening 11. Attention is directed to the fact that this 50 horizontal part is on a level with the top of the barrel. Also, the bottom of this passage is rounded transversely as better seen in Fig. 6. That portion of the casting above the opening 11 is substantially flat and between it and the partition 10, a fluid trapping chamber 12 is provided. Directly over the opening 11 is a hand-hole 13 permitting access to be had to the interior. This trapping chamber, which is in true vertical 55 alignment with the passage 9, empties thru a valve opening 14 above one end of the co-operating barrel. The opening is formed in a horizontal web which forms the bottom of a top discharge chamber 15, the top of 60 the latter being determined by the flattened

top of the casting. In said flattened top another hand-hole 16 is formed. As is obvious, this permits access to be obtained to the chamber 15. The latter permits the fluid to escape therefrom thru the discharge 70 conduit 6.

It should be noted that the suction intake passage 9 is substantially ovate or segmental in cross-section, while the chamber 12 and discharge chamber 15 are substantially rectangular in cross-section. As they are in superposed vertical alinement, the fluid takes a direct course therethrough. Here, I would also state that the outer end portions of the chambers are of box-like configuration, the 80 same being arranged in stepped relation. Further, the hand-holes are covered by removable cover plates 17 of the design shown and these are bolted or otherwise secured in place.

85 It is to be noted that I have not shown any valves, but have simply shown and described the casting. It is, of course, understood that in practice appropriate suction and pressure operated check valves are employed. For instance, valves of the type shown in my aforementioned patent may be used. In fact, in the devices which I have constructed and used, similar valves are used. Nor have I shown any lining in the 90 barrels. The linings may also be of conventional design to provide a smooth bore for the double acting pistons (also omitted).

95 By providing separate fluid trapping chambers 12, 12 for each suction valve and 100 separate discharge chambers 15, 15 for each discharge valve the cross cutting or back lashing of the fluid from one valve to another is reduced to a minimum. Because 105 of these separate chambers or compartments 12, 12 and 15, 15 for each of the suction and discharge valves, respectively, the sounding of the valves and the action of the pistons on this duplex type of pump, indicate 110 which valve, (if any) is not functioning properly. If the suction and discharge valves were each in a common chamber it would be impossible to tell which valve was 115 out of order without examination of all. Figure 2 shows in dotted lines at left, portions depending from roof portions of chambers 12 and 15 for restricting somewhat the outlet of fluid therefrom.

120 By carefully observing the drawings, I am confident that one skilled in the art to which the invention relates will understand 125 that the fluid column follows the course indicated by the arrows in Fig. 7. For instance, on the suction stroke of the plunger, the fluid is drawn in thru the open end of the intake manifold 5, passing upwardly thru the passage 9 and thru the opening 11 which is then uncovered by the unseated valve. On the return or pressure stroke of 130 the plunger, the fluid which has then been

trapped in the chamber 12, is forced up thru the valve opening 14, and discharge chamber 15 into the discharge conduit 6. It escapes from the conduit at the open end, 5 which is on the outside of the casting.

From the foregoing it will be seen that whereas the fluid was compelled to take a rather long and tortuous course in the patented device, it now takes the most direct 10 and shortest route possible with the present arrangement. There are no violent turns to impede the flow. On the other hand, the passages are so shaped and related, that easy flow is assured and no obstructions are 15 encountered.

The most prominent feature of the invention is the single metal casting embodying symmetry and a well balanced arrangement 20 of the chests, barrels, intake manifold, and discharge conduit. The last three details are in substantial parallelism with each other and confined within the areas of the comparatively larger end chests. The oppositely directed branch passages of the last 25 named details carry the fluid to the outsides of the opposite ends of the barrels instead of to the inner central portions. As stated, this arrangement shortens the travel of the fluid about 40%. As a result, greater speed 30 is attained, friction is reduced to a minimum, and less power is required to operate the pump.

Another thing, in the present structure, the details are more or less isolated from 35 each other, this being obtained by coring out the casting in between the barrels, chests, etc. Thus, all external walls are exposed to view for the purpose of detecting casting defects and leaks. This too, allows for expansion and contraction and makes for excellent aeration and permits repairs to be 40 readily made.

Furthermore, a constant fluid level is maintained by having the suction valve seats 45 on a plane with the top of the piston barrels. Priming is never necessary with this pump. Hence, the formation of air pockets is entirely eliminated. Then too, there is no excess lift of the fluid. These and other features and advantages have doubtless been 50 made apparent from the foregoing description taken in connection with the accompanying drawings. Therefore, a more lengthy description is thought unnecessary.

55 I claim:-

1. In a fluid pump of the class described, a fluid circulation unit comprising a single casting including a pair of parallel and horizontally disposed open ended barrels in 60 which separate pistons are adapted to travel; an intake manifold on a plane below and between said barrels; a pair of substantially arcuate fluid passages communicating at their lower and inner ends with said intake 65 manifold and leading upwardly in opposite

directions toward the outer sides of said barrels; separate fluid trapping chambers disposed outwardly from each of said barrels; said chambers having suction valve seats in their bottoms and in a plane with 70 the tops of the bores of said barrels, the upper ends of said arcuate passages communicating through said valve seats; the inner end of each of said fluid trapping chambers communicating with the adjacent barrel, 75 each fluid trapping chamber having an outlet directly above its barrel; a separate discharge chamber for each of said fluid trapping chambers and having seats for discharge valves through which said trapping 80 chamber outlets communicate; a discharge conduit above and between said barrels and said discharge chambers having communication with said discharge conduit.

2. In a fluid pump of the class described, 85 a fluid circulation unit comprising a single casting including a pair of parallel and horizontally disposed open ended barrels in which separate pistons are adapted to travel; an intake manifold on a plane below and between said barrels; a pair of substantially arcuate fluid passages communicating at their lower and inner ends with said intake 90 manifold and leading upwardly in opposite directions toward the outer sides of said barrels; separate fluid trapping chambers disposed outwardly from each of said barrels; said chambers having suction valve 95 seats in their bottoms and adjacent their outer ends, said valve seats lying in a plane with the tops of the bores of said barrels, the upper ends of said arcuate passages communicating through said valve seats; the inner end of each of said fluid trapping chambers communicating with the adjacent barrel, 100 each fluid trapping chamber having an outlet directly above its barrel; a separate discharge chamber for each of said fluid trapping chambers and having seats at their outer ends for discharge valves through 105 which said trapping chamber outlets communicate; a discharge conduit above and between said barrels, and the inner ends of said discharge chambers having communication with said discharge conduit.

3. In a fluid pump of the class described, 110 a fluid circulation unit comprising a single casting including a pair of parallel and horizontally disposed open ended barrels in which separate pistons are adapted to travel; an intake manifold on a plane below and between said barrels; a pair of substantially arcuate fluid passages at either end of the barrels communicating at their lower and inner ends with said intake manifold and 115 leading upwardly in opposite directions toward the outer side of said barrels; separate fluid trapping chambers disposed outwardly from each of said barrels; said chambers having suction valve seats in their bottoms 120

and adjacent their outer ends, said valve seats and the bottoms of said fluid trapping chambers lying in a plane with the tops of the bores of said barrels, the upper end of 5 aid arcuate passages communicating through said valve seats; the inner end of each of said fluid trapping chambers having relatively restricted outlets communicating with the adjacent barrel; each fluid trapping 10 chamber having an outlet directly above its barrel; a separate discharge chamber for each of said fluid trapping chambers and having seats at their outer ends for discharge valves through which said trapping chamber 15 outlets communicate; a discharge conduit above and between said barrels and the inner ends of said discharge chambers having relatively restricted outlets communicating with said discharge conduit.

20 4. In a fluid pump of the class described, a fluid circulation unit comprising a single casting including a pair of parallel and horizontally disposed open ended barrels in which separate pistons are adapted to travel; an intake manifold on a plane below and between 25 said barrels; a pair of substantially arcuate fluid passages communicating at their lower and inner ends with said intake manifold and leading upwardly in opposite directions toward the outer sides of said barrels; separate 30 fluid trapping chambers disposed outwardly from each of said barrels; said chambers having suction valve seats in their bottoms and adjacent their outer ends, said valve 35 seats and the bottoms of said fluid trapping chambers lying in a plane with the tops of the bores of said barrels, the upper ends of said arcuate passages communicating through said valve seats; the inner end of 40 each of said fluid trapping chambers having relatively restricted outlets communicating with the adjacent barrel, each fluid trapping chamber having an outlet directly above its barrel; a separate discharge chamber for 45 each of said fluid trapping chambers and having seats at their outer ends for discharge valves through which said trapping chamber outlets communicate; a discharge conduit above and between said barrels, and 50 the inner ends of said discharge chambers

having relatively restricted outlets communicating with said discharge conduit.

5. A fluid pump comprising the combination with a substantially horizontal piston barrel having a fluid discharge conduit in 55 communication therewith, of a fluid chamber contiguous to said barrel and in communication therewith, an inlet conduit communicating with said fluid chamber, said chamber having an inlet valve seat therein disposed in a plane tangential with the top of the 60 bore of said piston barrel.

6. A fluid end casting formed with a longitudinally extending piston barrel opening at each end into a fluid chamber, each 65 of said chambers being enlarged above said barrel laterally outward of the casting, an intake manifold extending longitudinally in the casting below said chambers and barrel, a fluid passage rising from each end of 70 said manifold below said chambers around the exterior thereof and vertically into said chamber enlargements, said chamber enlargement each having a bottom wall with its top face disposed in a horizontal plane 75 common with the top of the bore of said piston barrel, and a discharge conduit above said fluid chambers and piston barrel.

7. A fluid end comprising a casting formed with; a pair of spaced parallel, horizontal piston barrels extending longitudinally therein and open at each end into fluid chambers, an intake manifold disposed longitudinally in the casting below and between 80 said barrels with fluid passages rising at 85 each end externally around said fluid chamber and terminating in inlet valve seats in a common horizontal plane level with the tops of the bores of said barrels, discharge valve seats in the tops of said fluid chambers above said suction valve seats and in alignment therewith transversely of the casting, and a discharge conduit extending longitudinally in the casting above and between 90 said barrels and fluid chambers and in vertical alignment with said intake manifold.

In testimony whereof I hereunto affix my signature.

LEE J. BLACK.
